UNITED STATES PATENT OFFICE

WILLIAM P. DAY, OF CLEVELAND HEIGHTS, OHIO

ROADBED CONSTRUCTION

Application filed July 15, 1929. Serial No. 378,231.

This invention relates to a roadbed construction for street or boulevard railways and the main object of the invention is to provide a roadbed construction in which water will be 5 drained away from the bases of the rails and prevented from seeping in around the rail plates.

Another object of the invention is to provide a roadbed construction of the character 10 described in which the rails are supported upon a lower layer or foundation of concrete which is provided with drain openings to permit the water to escape away from the bases of the rails.

15 A further object of the invention is to provide a roadbed construction of the character described which consists of a foundation of concrete provided with suitable drain openings for draining the water away from the rail bases and in which the upper portion of the 20 roadbed is formed of a layer of material which is readily removable to permit the rails to be replaced or repaired.

A further object of the invention is to provide 25 a roadbed construction in which the bases of the rails are covered with a waterproofing material which tends to direct the water away from the rails and into suitable drain openings.

30 A still further object of the invention is to provide a roadbed construction of the character described which is provided with a centrally disposed drain or drain conduit which is disposed between the rails and from which 35 lead branch drain conduits leading to points adjacent the bases of the rails and along each side thereof.

A still further object of the invention is to provide 40 a roadbed construction of the character described which consists of a concrete foundation on which are supported steel ties of the twin type which are so arranged as to permit the material under the rail plates to be retamped when necessary or desired and in 45 which the upper layer of road forming material is readily removable to permit access to the rails or the removal of the same.

Further and more limited objects of the 50 invention will appear as the description proceeds and by reference to the accompanying

drawings in which Fig. 1 is a fragmentary plan view of the roadbed before the upper layer of road forming material is poured and disclosing the centrally disposed drain openings and the branch drain openings adjacent the bases of the rails and also disclosing the preferred type of tie; Fig. 2 is a vertical sectional view on the line 2—2 of Fig. 1; Fig. 3 is a vertical sectional view on the line 3—3 of Fig. 1.

Referring now to the drawings, reference character 1 designates the bottom layer of concrete which will be referred to as the foundation. Disposed below the foundation and between the rails is a drain conduit 2 which extends longitudinally of the track and parallel therewith. Arranged at intervals about three feet apart and extending across the roadbed are trenches 3 from which lead branches 4, 4^a, and 5, 5^a. The trenches 3 and the branches 4, 4^a and 5, 5^a are filled with gravel, stone, cinders or other suitable material adapted to permit water to drain therethrough and into the main drain conduit 2 which is preferably formed of drain tile. 70 Supported upon the foundation 1 are ties 6 which are preferably made of steel and are of the twin type. The ties consist essentially of rail plates 7 and 8 which are connected by cross bars 9 and 10. The rail plates are provided with oppositely disposed pairs of T-shaped openings 11 and 12 which are adapted to receive tie clamps for securing the rails in place.

The ties are supported on the foundation 85 and the cross beams or bars 9 and 10 are partially embedded therein as shown most clearly in Fig. 2. The foundation is first laid with the rails supported in the position shown in Fig. 2 and the concrete is allowed to harden 90 and set. The space beneath the rail plates 7 and 8 is filled with suitable material which is tamped in place in a manner well known to those skilled in the art. The rails 13 and 14 are first secured to the rail plates by means of suitable tie clamps. The rail plates and the bases of the rails are then covered with a waterproof material known as bituminous concrete which consists essentially of slag and crude asphalt in approximately the 95 100

following proportions: 3 parts fine slag, 2 parts course slag, 1 part crude asphalt.

A second layer of concrete 15 is then laid up to the level indicated by the line $a-a$ of Fig. 2. After this layer of material has hardened and set, a layer of surface material 16 is then applied which may consist of asphalt or any other suitable material.

According to the preferred manner of forming the roadbed construction hereinbefore described, I first provide a trench of suitable depth and which is slightly wider than the track. I then place between the track and adjacent the bottom of the trench the main drain conduit 2 which is preferably formed of drain tile. Suitable forms are then inserted to provide the trenches 3 and the branch drain openings 4, 4^a and 5, 5^a leading to points adjacent the opposite edges of the rails. The ties are then arranged in place and supported on suitable blocks and the rails secured thereto in a manner well known to those skilled in the art. The lowermost layer or foundation of concrete is then poured in a manner well known to those skilled in the art and allowed to harden and set. The spaces beneath the rail plates are then filled with suitable material and tamped in place by means of a tamping machine or in any other manner desired. The rail plates and the bases of the rails are then covered with a layer of bituminous concrete up to about the level shown in Figs. 2 and 3. The second layer of concrete is then poured up to the level indicated by the line $a-a$ in Fig. 2 and allowed to harden and set. The layer of surface material 16 is then applied in any suitable manner. By referring to the drawing, it will be seen that the branch drain conduits extend only through the road foundation and terminate at points adjacent the bases of the rails and also adjacent the rail plates. These drain openings are preferably about three feet apart and extend along both sides of the rails.

It will now be clear that any water which may seep in along the rails will strike the layer of bituminous concrete which is waterproof and be deflected into the branch drains 4, 4^a and 5, 5^a and drain into the main conduit 2. It will also be clear that the upper layers of material may be removed down to the foundation without disturbing the rails so as to permit removal or replacement of the track or retamping of the ties without disturbing the foundation. With this construction I am able to practically prevent any water from seeping in around the bases of the rails or the rail plates.

Various changes may be made in the manner of assembling and arranging the various parts without departing from the spirit of the invention. My invention is also not limited to any particular type of road forming material either for the foundation or for the uppermost layers. While I have in this

specification used the term "concrete" it is to be understood that I do not intend by this to limit the invention to any specific mixture of material but rather to use the term generically as embracing all of that class of materials in which a suitable bonding material such as cement or asphalt is used in connection with gravel, stone or sand. It is therefore to be understood that the invention is limited only in accordance with the scope of the appended claims.

Having thus described my invention, what I claim is:

1. In a roadbed construction for railways, a concrete foundation, a plurality of cross ties resting on said foundation, rails secured to said ties, a waterproof material covering said ties and the bases of said rails, a layer of concrete covering said foundation and a layer of surface material covering said layer of concrete, a drain conduit disposed between said rails and a plurality of branch drain conduits leading from points adjacent the rails and adapted to deliver into said first mentioned conduit. 90

2. In a roadbed construction for railways, a concrete foundation, a plurality of cross ties resting on said foundation, rails secured to said ties, a waterproof material covering said ties and the bases of said rails, a layer of concrete covering said foundation and a layer of surface material covering said layer of concrete, a drain conduit disposed between said rails and a plurality of branch drain conduits leading from points adjacent the rails and adapted to deliver into said first mentioned conduit, said branch drain conduits extending only through said foundation and terminating adjacent the bases of said rails, 100

3. In a roadbed construction for railways, a concrete foundation, a plurality of cross ties resting on said foundation, rails secured to said ties, a waterproof material covering said ties and the bases of said rails, a layer of concrete covering said foundation and a layer of surface material covering said layer of concrete, a drain conduit disposed between said rails and a plurality of branch drain conduits leading from points adjacent the rails and adapted to deliver into said first mentioned conduit, said branch drain conduits extending only through said foundation and terminating adjacent the bases of said rails, said waterproof material consisting of bituminous concrete and being disposed so as to deflect water into said branch drain conduits. 110

4. A roadbed construction for street or boulevard railways comprising a concrete foundation, a plurality of ties supported on said foundation, rails secured to said ties, a layer of waterproof material covering the bases of said rails and the end portions of said ties, a main drain conduit disposed between said rails, branch drain conduits leading from said main drain conduit and terminating ad- 125 130

ja⁵cent the rail bases and road forming material filling the space between and along said rails.

5. A roadbed construction for street or boulevard railways comprising a concrete foundation, a plurality of ties supported on said foundation, rails secured to said ties, a layer of waterproof material covering the bases of said rails and the end portions of said ties, a main drain conduit disposed between said rails, branch drain conduits leading from said main drain conduit and terminating adjacent the rail bases and road forming material filling the space between and along said rails, said branch drain conduits extending only through said foundation and terminating adjacent the rail bases.

6. A roadbed construction for street or boulevard railways comprising a concrete foundation, a plurality of ties supported on said foundation, rails secured to said ties, a layer of waterproof material covering the bases of said rails and the end portions of said ties, a main drain conduit disposed between said rails, branch drain conduits leading from said main drain conduit and terminating adjacent the rail bases and road forming material filling the space between and along said rails, said branch drain conduits extending only through said foundation and terminating adjacent the rail bases, said waterproof material consisting of bituminous concrete and serving to deflect water into said branch drain conduits.

35 7. A roadbed construction for street or boulevard railways comprising a concrete foundation, a plurality of steel twin ties supported on said foundation and partially embedded therein, said ties having rail plates which are disposed in a plane above said foundation, a pair of rails secured to said rail plates respectively, a waterproof material covering said rail plates and the bases of said rails, a road forming material filling the space between and along said rails, a main drain conduit disposed between said rails, a plurality of branch drain conduits leading from points adjacent the rail bases and adapted to deliver into said main drain conduit.

50 8. A roadbed construction for street or boulevard railways comprising a concrete foundation, a plurality of steel twin ties supported on said foundation and partially embedded therein, said ties having rail plates which are disposed in a plane above said foundation, a pair of rails secured to said rail plates respectively, a waterproof material covering said rail plates and the bases of said rails, a road forming material filling the space between and along said rails, a main drain conduit disposed between said rails, a plurality of branch drain conduits leading from points adjacent the rail bases and adapted to deliver into said main drain conduit, said branch drain conduits extending only

through said foundation and leading from opposite sides of the rails respectively.

9. A roadbed construction for street or boulevard railways comprising a concrete foundation, a plurality of steel twin ties supported on said foundation and partially embedded therein, said ties having rail plates which are disposed in a plane above said foundation, a pair of rails secured to said rail plates respectively, a waterproof material covering said rail plates and the bases of said rails, a road forming material filling the space between and along said rails, a main drain conduit disposed between said rails, a plurality of branch drain conduits leading from points adjacent the rail bases and adapted to deliver into said main drain conduit, said branch drain conduits extending only through said foundation and leading from opposite sides of the rails respectively, said waterproof material consisting of bituminous concrete and serving to deflect water from the bases of the rails into said branch drain conduits.

20 10. A roadbed construction for street or boulevard railways comprising a concrete foundation, a plurality of ties supported on said foundation, a pair of rails supported on said ties, a main drain conduit disposed between said pair of rails and having a plurality of branches leading therefrom and terminating adjacent the bases of said rails, road forming material filling the space between and along said rails, said road forming material being removable without disturbing said foundation.

11. A roadbed construction for street or boulevard railways comprising a concrete foundation, a plurality of ties supported on said foundation, a pair of rails supported on said ties, a main drain conduit disposed between said pair of rails and having a plurality of branches leading therefrom and terminating adjacent the bases of said rails, road forming material filling the space between and along said rails, said road forming material being removable without disturbing said foundation, said branch drains leading from opposite sides of said rails respectively and lying wholly within said foundation.

In testimony whereof, I hereunto affix my signature.

WILLIAM P. DAY.
